Jensen, Cincinnati, Ohio

Application February 15, 1939, Serial No. 256,604

5 Claims. (Cl. 237—8)

This invention relates to an air conditioning system and more particularly to a method and apparatus for independently controlling various portions of such a system.

5 An object of the invention is to provide a heating-cooling system so arranged that each room of a building will have its own independently operable thermostat and air conditioning unit, wherein the units in each room comprise 10 part of a larger, building encompassing system.

A further object of the invention is to provide an air conditioning system in which the heating media is positively circulated and supplied to each heat transfer unit in response to a heat demand 15 by any one of said heat transfer units.

Still a further object is to provide an electrical system for controlling the various units of the system comprising the invention.

These and other objects are attained by the 20 means described herein and disclosed in the accompanying drawing, in which:

Fig. 1 is a diagrammatic representation of a typical air conditioning system embodying the present invention.

25 Fig. 2 is a schematic wiring diagram of the system disclosed in Fig. 1.

It has long been customary to circulate suitable heating fluids through suitable heat transfer devices such as radiators and grilles and to 30 dissipate the heat from said heat transfer devices by means of fans which force a current of air through or over said heat transfer devices. However, when hot water is the media used to heat the heat transfer device, said device is too rapidly 35 cooled by the current of air blown over its coils with the result that although hot water is an economical heat distributing medium, the prior art devices do not develop such systems to the possible maximum efficiency. It is to obviate this 40 disadvantage that this invention is primarily directed.

As shown in Fig. 1, a typical multi-room set up 45 comprises a plurality of rooms or chambers A and B which are to be air conditioned. In each room a wall thermostat 10 and a unitary heat transfer device and blower 11 is provided. Suitable heat media is generated in a suitable boiler 12 which may, if desired, be located in a basement room C. The various heat transfer devices 11 are connected in parallel to boiler 12 by means of suitable riser and return pipes 13 and 14 as well known to the art. A suitable electrically driven hot water pump 15 is interposed in series with 50 said riser line, adjacent boiler 12 as shown.

55 Each heat transfer device 11 comprises a suit-

able radiator or coil 16 through which hot water is forced under pressure by means of pump 15. A fan assembly 17 mounted to the rear of said radiator or coil is adapted to blow or force air past said coils whereby to transfer the coil heat 5 to the room via the circulating air. The boiler, piping, unit radiator 11, fan 17 and thermostat 10, may all be of standard parts.

Reference is now made to Fig. 2 for a description of the electrical circuits embodied in said 10 system.

A constant source of electrical energy, such as main lead wires 20 and 21 is utilized to operate the control system. The desired temperature is maintained in any particular room as A or B by 15 means of a suitable thermostat 10 which controls the individual room blower circuits as well as the hot water pump circuit 15. One side of each blower motor 17 is electrically connected to power line 21 by means of conductor 22, binding post 20 23 and conductor 24. The blower motor circuit is completed through conductor 25, multi-speed motor switch 26, conductor 27 to binding post 28, conductor 29, bi-metallic thermostat arm 30, 25 thermostat contact members 31 or 32, which are connected in parallel to conductor 33 which terminates at power line 20. A choke coil 34 is connected in series with the multi-speed motor switch 26 as shown. Low speed contact tap 35 is connected to said choke coil by conductor 36; intermediate contact tap 37 by conductor 38; the high speed tap 39 serving as a terminal for the return conductor 40 of choke coil 34. This multi-speed switch choke coil hookup will be easily recognized by those skilled in the art. 35

The electrical circuit to water pump 15 comprises conductor 41 electrically connected directly to main line 21, the other portion of said circuit being connected to binding post 45 of relay unit 150 through conductor 42 to master pump control conductor 43 and conductor 44.

Electrical energy from conductor 20 is supplied to binding post 45 when armature 46 of relay 150 is pulled down upon contact arm 47 about a suitable hinge 48 in response to energization of coil 45 100 which is energized by reason of the operation of thermostat 10 which places said coil 100 across power lines 20 and 21. In this manner, the circuit to the motor of water pump 15 is completed, or closed simultaneously with the closing 50 of any blower fan motor circuit. The electrical circuit to said pump motor will remain closed so long as thermostat arm 30 contacts either of contact points 31 or 32, of any of the various room thermostats. However, only the blower circuit of 55

the particular room, the thermostat of which is completing an electrical circuit, will be energized.

It is to be understood that the relay unit 150, choke coil 34, multiple speed switch 26 and blower unit 17 may all be housed within a suitable cabinet unit indicated by the broken lines 48. Heat transfer unit 16 is likewise housed within said cabinet adjacent blower unit 17 as heretofore explained.

10 It should be noted that by reason of the electrical circuits described, the blower unit for each room is individually controlled and that each time the circuit of any blower unit motor is closed the electrical circuit to the motor of water pump

15 15 is likewise closed whereby to circulate hot water through each and every heat transfer unit of the system. It should be understood that the heating of each room is effected by reason of room air being blown over the heat transfer unit

20 coils and not by reason of radiation from said heat transfer units. By reason of this fact, the temperature of a room already at a predetermined temperature, will not be increased by reason of the circulation of hot water through its 25 heat transfer unit when pump 15 is set in operation by the demand for heating fluid in some other room. In this manner the heat dissipated in any single room is independent of the conditions and heat demands existing in other rooms,

30 although the heat transfer units in each room are mutually dependent upon the single source of heat supply, viz., boiler 12 and pump unit 15, the motor circuit of which is adapted to be closed by the thermostat of each room.

35 In operation the system functions as follows: The heating media, water, is constantly maintained at a suitable temperature in boiler 12, and although a certain amount of hot water will circulate through the riser and return pipes 13 and 40 14, respectively, due to the convection currents set up within the mass of hot water, the circulation relied upon for the purpose of heating the heat transfer units is dependent upon the motor driven water pump 15.

45 Assume now that the temperature in room A falls below the temperature setting of thermostat 10. This results in bi-metallic arm 30 contacting, say contact tap 31, which instantly closes the electrical circuits to blower unit 17 of room

50 A and at the same instant the electrical circuit to the motor of water pump 15 is closed whereby hot water is circulated through each heat transfer unit. If heat is not needed in room B, the blower unit for that room remains inoperative 55 and the heat being supplied to its coils 16 due to the operation of pump 15 is not dissipated into said room.

It should be noted that two contact taps 31 and 32 are provided in thermostat 10, one on either 60 side of bi-metallic arm 30. In this manner the system just described, may be adapted or converted into a room cooler for summer use by using the right tap 32 as the summer heat contact, as well understood in the art. When the 65 blower units are used to cool a room, switch 49 in pump circuit conductor 41 may be opened as indicated by the broken line 50 for disconnecting pump 15 from the system.

70 It should be understood that any number of similar units may be operated from the system disclosed. The multi-speed blower switch 26 is used in order to make the system more flexible, and by enabling a smaller coil 16 to be used in the heat transfer device, the size, cost and weight 75 of the room units are materially reduced. By

passing greater or lesser quantities of air over coils 16, more or less heat is delivered from the unit, said quantities of air being directly proportional to the speed of said blower fan 17.

If desired, outside air may be circulated by 5 blower fans 17 during the summer months, by providing suitable ducts in communication with the outside of the building, and located at each of the individual units.

It should be understood that water pump 15 10 may be placed in the return line 14, if desired, in lieu of the riser line 13 as shown.

Likewise various other modification and changes in the structural details of the device may be made, within the scope of the appended 15 claims, without departing from the spirit of the invention.

What is claimed is:

1. In a control system comprising a plurality of individual heat exchange units each including 20 blower means and individual motors for operating each blower means, each heat exchange unit connected in parallel to a common source of heat supply, heat media recirculating means in series with said source of heat supply, and a motor 25 for operating said means, each blower motor energized by an individual circuit, said recirculating motor being energized by a separate circuit, a separate thermostatic switch responsive to the temperature of the area heated by a heat 30 exchange unit for opening and closing each blower motor circuit, each thermostatic switch being in series with the recirculating motor circuit, means to supply electric current to all circuits, the circuit to the recirculating motor being 35 closed each time any individual blower motor circuit is closed.

2. A control system for a plurality of individual, independently operable blower motors and a single pump motor operable whenever any 40 blower motor is in operation and comprising a three wire electrical system, two of said wires electrically connected to a constant source of electrical energy, each of said blower motors being in one of a plurality of identical series circuits, comprising a blower motor, an electric automatic circuit closing means responsive to a predetermined temperature of the area under the influence of its blower, a relay unit, and electric current control means, each of said blower motor 45 circuits being connected in parallel across the two wires electrically connected to said constant source of electrical energy, said pump motor being electrically connected in series between one wire of said constant source of electrical energy 50 and said third wire, means for electrically connecting the second electrical supply wire to said third wire for completing an electric circuit to said pump motor when any of said blower motor circuits are completed, said means comprising an 55 armature contact arm in a series circuit with said second electrical supply wire and said third wire and adapted to close said circuit when said armature contact arm is actuated by energization of its associated relay unit whereby the circuit to 60 said pump motor is completed simultaneously with the completion of any of the individual independent blower motor circuits.

3. In a multiple zone heating system, the combination of a common source of heat supply, a 70 single fluid conduit system for conveying a heat media from the common source of heat supply to each of a plurality of zones and returning the heat media to the source of heat supply, a single electric motor driven impeller means operatively 75

associated with the fluid conduit system for circulating the heat media therethrough, a plurality of heat transfer units located one in each of a plurality of zones, each heat transfer unit connected in parallel to the fluid conduit system, a plurality of electric motor driven air circulating means operatively associated one each with each heat transfer unit, a plurality of electric automatic switching means responsive one each to the temperature of a separate one of said zones for controlling the operation of the air circulating means for that zone and for simultaneously controlling the operation of the impeller means for the entire fluid conduit system.

15 4. A three wire electrical control system for a multiple zone heating system comprising in combination a plurality of heat transfer units located one in each of a plurality of zones, electric motor driven air circulating means associated with each heat transfer unit, a common source of heat media, a closed heat media conduit system, each heat transfer unit connected in parallel in the heat media conduit circuit, a single electric motor driven heat media impeller means for circulating the heat media through the heat transfer conduit system, of a plurality of duplicate electrical circuits for controlling one each the operation of one air circulating means, each of said duplicate circuits comprising an electric automatic switch means responsive to predetermined temperatures of a separate one of said zones and being in series with the air circulating means of that zone, each of said duplicate cir-

cuits being connected in parallel across a two wire power line, said power line being electrically connected to a constant source of electrical energy, said heat media impeller motor connected in series with one power line and the third wire of the three wire system, said third wire adapted to be electrically connected to the second wire of the power line upon energization of any air circulating means circuit whereby the heat media impeller motor is operated continuously and simultaneously with the operation of any air circulating motor.

5 5. A control system comprising a plurality of individual heat exchange units, blower means associated with each heat exchange unit, individual motors for driving each blower means, a closed heat media circuit, a common heat media circulating means for distributing heat media to all of the heat exchange units, a motor for driving said heat media circulating means, an individual electrical circuit for controlling the operation of each blower motor, a common electrical circuit for controlling the operation of the circulation motor, a thermostatically controlled electric switch means controlled by an external condition for controlling the operation of each of said blower motors and for concurrently controlling the operation of the circulator motor.
